GEORGE C. WALKER, OF WAYNE, MICHIGAN, ASSIGNOR OF ONE-HALF TO THOMAS M. LUCKING, OF DETROIT, MICHIGAN

TRAFFIC SIGNAL

Application filed October 6, 1930. Serial No. 486,541.

This invention relates to a traffic signal, and has to do particularly with novel means for indicating the approximate time before a change in signals.

5 In standard traffic signals now generally in use, the change from one signal to another is instantaneous so that unless the motorist is unusually familiar with each individual traffic light the change in traffic in very slow 10 and confusing. Attempts have been made to indicate time of change by passing various indica over the face of the signal and by varying the extent of closure of the signal opening, but such devices have usually been 15 more or less complicated.

The primary object of the present invention is to indicate the approximate duration of a certain signal, or, in other words, the time remaining before the change of the signal, by shaping the light indicating field itself so that its inherent shape passing by the signal opening serves as a timing means. In this case, the timing may be individually controlled at each traffic signal and is preferably obtained by a rotating indicating field, the light source remaining fixed.

Another feature of the invention resides in the provision of means for instantly changing the signal from one color to the next as the existent indicating field approaches the end of its movement past the signal opening. In this case, the blank spaces between adjacent rotating indicating fields are eliminated and a full indicating field covers the opening until the next indicating field reaches its effective position.

In the drawings:

Fig. 1 is a vertical sectional view of a traffic signal embodying the features of the present invention and illustrating one means for raising and lowering the intermediate shutter structure.

Fig. 2 is a somewhat diagrammatic sectional view showing the shutter arrangement 5 in neutral position with the light field uncovered.

Fig. 3 is a view similar to Fig. 2 but showing the green shutter in raised position to fill in the space between the red rotating field and the green rotating field.

Figs. 4 and 5 illustrate a similar development to Figs. 2 and 3, but with the shutter unit in neutral position with the green rotating field showing and in lowered position with the red shutter intervening between the two 55 fields.

Fig. 6 is an elevation of a traffic signal embodying the present invention and showing the narrowing indicating field moving past the signal opening.

The gist of the present invention resides in a moving indicating field the shape of which visibly indicates the approximate time such field will remain before a given opening. Various types of structure and various 60 mechanical means may be utilized for rotating and controlling the operation of the predetermined shaped indicating fields and in Fig. 1 I have illustrated one form of device embodying the present invention.

Any suitable housing 1 may be provided with a plurality of apertures 2 which may be termed signal openings. A light source 3 may be stationarily supported from the top of the signal housing as best shown in Fig. 1, and a cylindrical rotatable drum 4 preferably surrounds this light source 3. The drum 4 may be rotated by any suitable means 5 which may consist of a motor or similar device the speed of which may be regulated at 65 each particular traffic signal or controlled from a common remote point.

The drum 4 is preferably provided with apertures 6, such apertures having a special shape, as best illustrated in Fig. 1, and being backed by a transparent colored means 7 such as celluloid or the like to form indicating fields. The length of each indicating field and the degree of taper may, of course, vary with different installations and particularly 70 with the size of such installations. In the ordinary standard traffic signal it will be obvious that diametrically opposite indicating fields will be of similar colors.

If desired, the horizontally tapered indicating fields 6 may be rotated past the apertures 2 without the use of any intervening shutter or the like. As each indicating field narrows down towards a point, it will be 75 obvious to any observer that a change of sig- 100

nals is about to take place. As a wide signal of different color starts across the signal opening this will indicate a change of signal.

To positively indicate the change in signals I prefer to use a shutter arrangement so that as the changing indicating field gradually comes down toward a point, indicating that the change is about to take place, the shutter will immediately and quickly cover the opening and such shutter will be of the same color as the oncoming indicating field with the result that when the oncoming indicating field assumes its position relative to the signal opening the shutter may be moved so as to allow the changing shape of the indicating field to indicate the approximate time of change of signals.

One form of shutter structure is illustrated in Fig. 1 and diametrically in Figs. 2 to 5. This shutter consists of a vertically movable cylinder 8, the vertical movement of said shutter being assisted by means of suitable grooves 9 formed in the housing 1. Each cylindrical shutter unit may be cut-away to form three apertures 10, 11, and 12, the aperture 10 being covered with red transparent material corresponding to the material used in forming the indicating field 6, the aperture 11 being open and the aperture 12 being covered with green transparent material.

The drum 4 may be provided with a suitable cam groove 13 and the cylinder shutter member 8 provided with a suitable pin 14 adapted to be actuated by said cam groove. As the drum 4 is rotated at its regular speed it will be obvious that the cylindrical shutter unit will be moved up and down according to the particular part of the shutter which is to cover the signal opening. In ordinary practice the central horizontal part of the cam groove will cause the shutter to remain in neutral position, such as shown in Figs. 2 and 4, a relatively long time, and in the top and bottom positions a relatively short time. The same light source 3 will provide sufficient light to illuminate the portions 10 and 11 of the shutter when such portions cover the signal opening.

The size of the signal opening 2 may vary considerably and is preferably smaller than the apertures 10, 11, and 12 of the shutter. Whether a cam groove, or other means, is used to operate the shutter such shutter is preferably actuated to cover the opening at a time when the passing indicating field narrows down to a point. The shutter drops across the opening between the time the end of the indicating field leaves the edge of the opening and the time it reaches the center of such opening, the preferred operation being at the very instant that the tail end of the indicating field reaches the first edge of the opening.

It will thus be seen that I have provided a traffic light the time of change of which is

indicated by a predetermined permanently shaped indicating field movable relative to a stationary signal opening. The mechanism is very simple and inexpensive and the timing of each signal may be regulated by merely increasing or decreasing the speed of movement of the drum carrying the indicating fields. The intermediate or yellow signal is dispensed with and but one light source is necessary.

It will be understood that a plurality of independent light sources may be embodied within the signal with the result that one or more of said light sources may fail without impairing the efficiency of the signal indicating means. Thus if my signal device is equipped with three sources of light as the ordinary traffic signal, it will be obvious that I obtain a safety factor three times as great as that of the usual traffic signal.

What I claim is:

1. A traffic signal of the type described, comprising a movable indicating field, certain sides of which are shaped to indicate the rate of change of said indicating field.

2. A signal comprising a relatively movable signal opening and indicating field, said indicating field being shaped to change its visible contour and indicate the time of change during said relative movement.

3. A signal comprising a relatively movable signal opening and indicating field, one of said members being shaped to visibly indicate by a change in contour the approximate time of change during said relative movement.

4. A traffic signal comprising a stationary light source, a fixed signal opening and a specially shaped indicating field positioned between the light source and said opening and movable relative to the opening to visibly indicate by a changing contour the approximate time said field remains.

5. A traffic signal comprising movable indicating fields having gradually changing contours to visibly indicate the time left before a change in signal and separate means for covering the space between the indicating fields.

6. A traffic signal comprising a stationary light source and a housing having an opening and a plurality of indicating fields rotatable past said opening, said indicating fields being shaped to visibly indicate the approximate rate of change of a given indicating field, and signal means in the form of a shutter member over said opening during the change between one signal and another signal.

7. A traffic signal comprising a stationary light source and a housing having an opening and a plurality of indicating fields rotatable past said opening, said indicating fields being shaped to visibly indicate the approximate rate of change of a given indicating field, and signal means in the form of a shutter mem-

ber over said opening during the change between one signal and another signal, said signal means being of the same color as the oncoming indicating field.

5 8. Signal means comprising a signal opening and an indicating field movable past said opening, said indicating field being shaped so as to gradually merge towards a central point as it passes by said opening whereby to indicate the approximate time said indicating field takes to pass said opening.

10 9. Signal means comprising a signal opening and an indicating field movable past said opening, said indicating field being shaped so as to gradually merge towards a central point as it passes horizontally by said opening whereby to indicate the approximate time said indicating field takes to pass said opening.

15 10. A signal device comprising a light source, a signal opening, an indicating field illuminated by said light source, said indicating field and said signal opening being relatively movable and shaped whereby said relative movement will cause a change in the shape of the visible part of the indicating field to indicate the approximate time of change.

20 11. A signal device comprising a light source, a signal opening, an indicating field illuminated by said light source, said indicating field and said signal opening being relatively movable and shaped whereby said relative movement will cause a change in the shape of the visible part of the indicating field to indicate the approximate time of change, and a transparent shutter means for covering said opening at a certain predetermined time during the relative movement between said indicating field and opening.

25 12. A signal device comprising a light source and a rotatable indicating field, said indicating field having angularly positioned sides tapering towards a point whereby to indicate the approximate time of change between one indicating field and the next.

30 13. A signal device comprising a light source, a single visible signal opening for each particular direction, a colored indicating field having a predetermined shape, and means for causing relative movement between the indicating field and said single opening whereby the shape of said indicating field gradually changes to visibly indicate the time left before a change in signal.

35 14. A signal device comprising a light source, a visible signal opening for each particular direction, an indicating field movable past said opening, and means forming a part of said indicating field for visibly indicating the approximate rate of change and time left before a change in signal.

40 15. A signal device comprising a light source, a visible signal opening for each particular direction, an indicating field movable

45 past said opening and means forming a part of said indicating field and gradually changing in dimensions for visibly indicating the approximate rate of change and time left before a change in signal.

50 In testimony whereof I affix my signature. ⁷⁰
